Attns.

UNITED STATES PATENT OFFICE

FRANK KUSTERLE, OF KENOSHA, WISCONSIN, ASSIGNOR TO SIMMONS COMPANY, OF KENOSHA, WISCONSIN, A CORPORATION OF DELAWARE

SIDE-RAIL LOCK

Application filed June 2, 1923. Serial No. 643,075.

My invention relates to fastening devices for detachably securing the side rails of a bed to the bed ends.

The principal objects of my invention are 5 to provide a connection of so simple a form that it may be readily assembled and taken apart by inexperienced persons; to avoid the necessity of using tools or wrenches in connecting or disconnecting the rails and bed 10 ends; to dispense with loose parts; to insure a permanent rigid connection; to construct the parts of rolled or stamped metal and thereby eliminate possibility of breakage; to reduce the number of parts to a minimum; to 15 utilize the end of the side rail as a bearing face for holding the bed end in upright position; and to provide a neat and compact corner fastening which may be readily applied to various types of corner posts.

20 Referring to the drawings:

Fig. 1 is a side view of a corner connection embodying my improvements;

Fig. 2 a sectional view thereof, taken substantially on the line 2—2 of Fig. 1;

25 Fig. 3 a top view of the corner connection showing the construction of the remote end of the side rail;

Fig. 4 an enlarged detail view of the bracket seat for confining the end of the up- 30 right flange of the side rail; and

Fig. 5 a view similar to Fig. 2, showing the side rail in reverse position.

On the drawings, the reference numeral 1 indicates a fragmentary portion of a tubular 35 bed post, 2 a side rail of the bed and 3 a bracket for securing the side rail to the bed post. This bracket 3 comprises an upright elongated plate portion 4, the outer face of which is formed to correspond to the form 40 of the post to which it is to be attached, in the present case the outer face of the plate 4 being concave to fit the circular post 1. This plate is clamped onto the post by cap screws 5, or rivets if desired, which are passed 45 through apertures near the upper and lower ends of the plate 4 and through corresponding apertures in the wall of the post 1 and are secured to a washer 6 inside the post, so as to clamp the wall of the post between the plate 50 4 and washer 6. At the outer edge of the

plate 4 the bracket 3 is formed with a wing 7 having a vertically elongated notch 8 formed therein which is open at the top, the forward edge of said notch being arranged at a slight angle to the plane of the plate 4 as shown in Fig. 1, so as to afford a wedge action as hereinafter described, for clamping the end of the side rail against the plate 4. The bracket 3 is preferably of pressed or rolled metal and the notch 8 is formed therein by stamping or punching the section of metal within the notch outwardly from the side wing 7 in such a manner that the front bearing edge shears off on a slight bevel as shown at 9. 65

The side rail 2 is in the form of an angle iron and has a headed stud 10 secured to the upright flange thereof a short distance from each end. This stud is arranged substantially midway between the upper and lower edges 70 of the side flange of the angle iron and is preferably somewhat tapered as shown particularly in Fig. 3, to insure a tight fit in the aperture of the rail flange and also to co-operate with the bevel edge 9 of the notch 75 8 so as to afford a lateral drawing of the upright flange of the rail against the side wing 7 of the bracket, and the inner end of this stud is upset or riveted over against a washer 11 which is placed against the inner 80 face of the upright flange of the angle iron side rail.

It is desirable in bed constructions to have the angle iron side rails arranged so that they may be reversed, that is, so that they may be 85 positioned with the horizontal flange at the top as shown in Fig. 2, or with the horizontal flange at the bottom as shown in Fig. 5. In the present construction the end of the angle iron butts against the plate portion 4 of the bracket 3, and in order that the horizontal flange may clear the upper cap screw or rivet 5, the ends of the angle iron are notched as at 12, said notch being extended so that the inner side thereof is substantially flush with 90 the inner surface of the upright flange of the angle iron, and forms a tongue 13 at each end of the angle iron consisting of the end portion of the upright flange of the angle iron and also a narrow tongue 14 at each end. 10

consisting of an end portion of the horizontal flange of the angle iron. At the junction of the side wing 7 with the plate 4 the bracket 3 is formed with an upwardly extending flaring groove, channel or recess 15 of a form substantially as shown in Fig. 4, which is engaged by the tongue or projecting end 13 of the upright flange of the angle iron when the stud 10 is engaged in the wedging notch 8, said channel or recess 15 being adapted to confine the end of the tongue 13 and hold same rigidly against lateral displacement. The engagement of the tapered portion of the stud 10 with the beveled edge 9 of the notch 8 serves at the same time to increase the rigidity of the connection by drawing the side flange of the angle iron laterally against the side wing 7 of the bracket 3, such lateral drawing action being also supplemented by the engagement of the projection or tongue 14 of the horizontal flange of the angle iron against the plate portion 4 of the bracket, as the tongue or projection 13 of the upright flange is inserted into the seat 15.

It will be observed that because the pin or stud projects laterally from the plane of the vertical flange of the side rail, the thrusts or reactions of the bracket parts against the end 13 of the flange and against the shank 30 of the pin 10, are substantially out of line or offset so as to provide a twisting couple or moment between the bracket and the rail which also tends to draw the free end of the wing 7 and the vertical flange of the side rail into intimate contact. There is no tendency for the end 13 of the side rail to slip on the plate part 4 of the bracket for the reason that the end 13 of the side rail is rigidly wedged or anchored in the groove 15.

It is customary to connect the two posts of each bed end by means of a cross rail which is usually located at about the same elevation as the side rail of the bed, and in my present construction this cross rail, which is indicated at 16, is arranged somewhat below the lowest position of the side rail 2, so as to afford ample clearance, and has the ends connected to the post 1 by means of the lowermost cap screw or rivet 5 which serves to secure the bracket 3 to the post. The side wings 7 of the bracket 3 are positioned at the outer side of the plate 4, and these side wings therefore conceal the ends of the cross brace 16 and the parts which connect the brackets 55 to the post 1, and the corner fastening therefore presents a neat compact appearance.

With this construction, it will be observed that the side rail 2 may be readily reversed by turning same endwise and the ends of the side rail interlock with the bracket 3 in the same manner in either position.

While I have shown and described my invention in a preferred form, I am aware that various changes and modifications may be made without departing from the principles

of my invention, the scope of which is to be determined by the appended claims.

I claim as my invention:

1. In a bedstead corner fastening, the combination of a corner post, a plate bent to form a wing member having a flange extending laterally therefrom, said flange being secured to the post and provided with a vertically extending seat adjacent the wing member, and said wing member being provided with an open top notch, an angle iron side rail having an upright flange and a horizontal flange, a lateral projecting stud on said upright flange wedgingly engaging the notch of the wing member so as to jam the end edge of said flange into the aforesaid seat, said notch being provided with a beveled bearing edge and the stud with a tapered stem for engagement with the beveled edge whereby the upright flange of the angle iron is wedged against the wing member of the bracket.

2. In a bedstead corner fastening, the combination of a corner post having a bracket attached thereto, a portion of said bracket projecting therefrom, said projecting portion having an open-ended slot therein formed with an edge inclined toward the post at its lower end, said edge being beveled, and a side rail having a laterally projecting stud having a tapered shoulder adapted to engage said beveled edge of said slot whereby clamping engagement is effected between the side of said rail and said bracket, and also between the end of said rail and another portion of said bracket.

3. In a bedstead corner fastening, the combination of a corner post, a bracket having a vertically extending plate secured to the post and a vertically extending wing projecting outwardly from one side of said plate, and having an inclined slot formed therein, a side rail having an end part disposed against the inside of the wing and having its extremity engaged in the angle of the bracket, and a pin secured to said end part and projecting laterally into said slot to wedge said end part against the plate, the inter-engaging parts of the pin and slot being relatively beveled so as to draw the end part into intimate contact with the wing.

FRANK KUSTERLE.
